UNITED STATES PATENT OFFICE

2,050,241

THREAD-TENSION MECHANISM FOR
SEWING MACHINESRudolph Becker, North Plainfield, N. J., assignor
to Singer Manufacturing Company, Elizabeth,
N. J., a corporation of New Jersey

Application April 2, 1935, Serial No. 14,218

8 Claims. (Cl. 112—255)

This invention relates to thread-tension mechanism for sewing machines, more particularly of the single-thread straw-braid-sewing type, such as represented in United States Patents No.

- 5 1,429,399, of Sept. 19, 1922; and No. 1,680,721, of
Aug. 14, 1928. Machines of this type commonly
employ hook and eye-pointed needles which are
simultaneously projected upwardly through the
work. Suitable looper devices above the work
10 seize a loop of thread from the eye-pointed
needle and present it to the hook-needle which
pulls such loop downwardly through the work.
The work is then fed a stitch-length by the usual
feed-dog and, on the next upstroke of the needles,
15 the eye-pointed needle passes through the loop
of thread previously pulled down by the hook-
needle.

Machines of the type in question must be
capable of sewing over a wide range of feed-ad-
20 justments varying, say, from a stitch-length of
 $\frac{1}{8}$ inch to a stitch-length of $\frac{5}{8}$ inch; thread-re-
quirements for this variation in stitch-lengths
running, roughly, from $\frac{3}{8}$ inch to $1\frac{1}{8}$ inches of
thread per stitch. Various intermittent tension
25 devices have heretofore been proposed to meet
this wide variation in thread-requirements for
the different stitch-lengths but none of them is
sufficiently versatile to meet the wide range of
sewing conditions met with in practice.

30 The present invention therefore has for an ob-
ject to provide an intermittent tension mecha-
nism which is capable of adjustment to meet sew-
ing conditions over a wide variety of materials
and stitch-lengths. Another object of the inven-
35 tion is to provide an intermittent tension mecha-
nism which is of compact construction and re-
quires but little space within the machine bed for
its installation. A further object of the inven-
tion is to provide a simplified intermittent thread-
40 tension mechanism the action of which is variable
and is regulated by adjustment of the work-feed-
ing mechanism. Still further, the invention has
for an object to provide a variable intermittent
tension mechanism which will function efficiently
45 at high speed over its entire range of adjustments.

With the above and other objects in view, as
will hereinafter appear, the invention comprises
the devices, combinations, and arrangements of
parts hereinafter set forth and illustrated in the
50 accompanying drawings of a preferred embodiment
of the invention, from which the several fea-
tures of the invention and the advantages attained
thereby will be readily understood by those skilled
in the art.

55 A feature of the invention, in one of its as-

pects, is the provision of a main cam functioning
in the shortest stitch-length adjustment of the
machine to hold the tension device open for the
shortest length of time and the provision of a plu-
rality of selectively controlled auxiliary cams 5
which function individually to control the ten-
sion-device at other periods of the cycle when the
main cam has ceased to function.

In the accompanying drawings, Fig. 1 is a
transverse vertical section through the bed of a 10
straw-braid sewing machine embodying the in-
vention; the mechanism being set at the longest
stitch-length adjustment. Fig. 2 is a similar view
with the mechanism set at the shortest stitch-
length adjustment. Fig. 3 is a plan view of the 15
mechanism. Fig. 4 is a disassembled perspective
view of the auxiliary cam-follower devices and
the supporting means therefor which constitute
a part of the present variable intermittent tension
mechanism, and Fig. 5 is a detail view of the 20
yoked end of the tension-control rod.

The machine, in general, is constructed sub-
stantially in accordance with the disclosure of the
United States Patent No. 1,429,399, referred to.
It includes the bed 1, cloth-plate 2, needles 3, feed- 25
dog 4 and main shaft 5. The feed-dog 4 is
mounted on the feed-bar 6 which is pivotally
mounted at 7 on the feed-rocker 8 fulcrumed at
9 on the machine bed.

The feed-lift mechanism is as usual and is pref- 30
erably constructed substantially in accordance
with the disclosure of United States Patent No.
1,397,071, of Nov. 15, 1921. Such mechanism in-
cludes a feed-lift link 10 pivotally connected at
its upper end at 11 to the feed-bar 6 and at its 35
lower end to a pin 12 receiving up-and-down
movements from the main shaft through a suit-
able pitman 13 guided at its lower end in the slot
14 in the swivelled head 15.

The feed-bar 6 is given its feed-and-return 40
movements by the usual forked pitman 16 pivot-
ally connected at 17 to the feed-rocker 8. The
forked end of the pitman 16 embraces the usual
cam-follower block 18 surrounding the feed-ec-
centric 19 on the main shaft 5. The pitman 16 is 45
connected at 20 to one end of the anchor-link
21 the other end of which is connected at 22 to the
feed-regulator lever 23 fulcrumed on the pin 24
journalized in the frame-lug 25. The feed-regu-
lator lever 23 projects outwardly through the 50
machine bed and has slidably mounted thereon
a handle 26 influenced by the spring 27 to carry
the detent teeth 28 at the base of the handle
into a selected one of the detent notches 29 in
the rack-bar 30 secured to the bed 1. In the ma- 55

chine illustrated there are five notches 29 in the rack-bar 30 which provide five predetermined stitch-length settings for the feed-regulator 23, evenly spaced from the longest stitch-length, 5 Fig. 1, to the shortest stitch-length, Fig. 2.

The tension device comprises a seat 31 in the form of a cylindrical plug which is mounted in an aperture 32 in the bed 1 and is adjustably held in set position lengthwise of the axis of such aperture by the set-screw 33 bearing upon the flat 33' extending lengthwise of the seat 31. The seat 31 has a thread-tension face 34, Fig. 3. Slidably mounted in the seat 31 is the rod 35 the outer end-portion of which is reduced in diameter to 10 form a shoulder 36. Freely mounted on the rod 35 between the shoulder 36 and a collar 37 screwed onto the reduced and screw-threaded end of the rod 35 is the tension-head 38 which is yieldingly urged toward the shoulder 36 by the spring 39 15 backed by the adjusting nut 40. The collar 37 may be adjusted or set at any desired distance from the shoulder 36 to provide a limited amount of play of the tension-head 38 lengthwise of the rod 35 between the shoulder 36 and collar 37; 20 a set-screw 37' holding the collar 37 in any position of adjustment.

The rod 35 is provided at its inner end with a yoke 41 which supports the pin 42 on which is journaled the roller 43. The yoke 41 has projecting portions 44 which are guided in slots 45 in the inner end of the seat 31 to maintain the axis of the roller 43 in parallelism with the main shaft 5. A relatively strong spring 46 reacting against the seat-member 31 urges the yoke 41 in a direction to close the tension-head 38 strongly against the face 34 of the tension-seat 31.

Fixedly mounted on the main shaft is a nest of tension-release cams including a primary or main centrally disposed cam 47 and four differently 40 and individually shaped auxiliary cams 47' arranged two at either side of the primary cam 47 which is larger in diameter than the auxiliary cams 47'.

The primary cam 47 acts directly upon the 45 roller 43 to open the tension-device, whereas the auxiliary cams act upon the roller 43 through a group of follower bars 48 having thickened cam-engaged portions 49 arranged at individually different positions lengthwise of said bars. The 50 cam-follower bars 48 are pivoted on the pin 50 carried by the lever 51 fulcrumed at 52 on the frame-lug 53. The lever 51 is formed between its ends with a slot 54 which is entered by the roller-stud 55 projecting laterally from the upward extension 56 of the feed-regulator lever 23.

When the feed-regulator lever is set with its handle 26 at its lowest position, Fig. 2, for production of the shortest stitch, the thread-requirements of the stitch-forming mechanism are at a 60 minimum and the bars 48 are elevated to their highest point relative to the auxiliary cams 47', at which point all are inoperative as none of the thickened portions 49 is operatively engaged by an auxiliary cam 47'. This setting allows the 65 primary cam 47 only to control the time of opening of the tension device. The high portion of the primary cam 47, which lies within the acute angle $a-a$, has a comparatively short angular extent of about 120° and is timed to fully open 70 the tension-device as the rising needles enter the work and fully close the tension-device as the needles are nearing the end of their downstroke.

When the handle 26 is raised to the next higher notch 29 in the rack 30 to increase the stitch-length, the bar 48 having the lowest thickened

portion 49 is selectively positioned for operative engagement by its respective auxiliary cam 47', shown in section in Fig. 2, the function of which is not to open the tension-device any wider than it would be opened by the primary cam 47, but to prolong the time the tension is held open; the high portion of the auxiliary cam between the points, b , c functioning to hold the tension open for a short time after it would have been allowed to close by the primary cam 47 functioning alone. 10 It will be obvious that for each stitch-length adjustment a selection is made of one or another of the follower bars 48 which is operatively positioned relative to its respective cam 47' for the control of the tension-device. 15

While in the specific embodiment of the invention shown and described, the individual actions of the auxiliary cams cannot encroach upon the tension-opening action of the primary cam, they can selectively prolong the time the tension 20 is to remain open to meet the thread-requirements of the particular stitch-length adjustment. By omitting the primary cam and the shortest stitch-length adjustment, it is possible to have a plurality of independent tension-controlling cams 25 which are selectively controlled by the feed-adjustment and the action of each of which is quite independent of the others.

By adjusting the collar 37 toward or away from the shoulder 36 on the rod 35, and by adjusting 30 the seat 31 in the aperture 32, it is possible to allow the tension device to close with a light tension or with a strong tension, or to vary from a light tension to a strong tension without opening 35 at all. The provision of these adjustments increases the range of usefulness of the device to meet a wide variety of sewing conditions met with in practice, as will be readily understood by those skilled in the art.

Having thus set forth the nature of the invention, what I claim herein is:—

1. In a sewing machine, the combination with a rotary shaft and feeding mechanism including a four-motion feed-dog and a feed-regulator, of a spring-closed thread-tension device, a plurality of cams fixed on said shaft, and means connected to said feed-regulator for rendering any desired one of said cams operative upon said tension-device.

2. An intermittent thread-tension for sewing 50 machines including a spring-closed tension-device, a rotary shaft, a nest of tension-opening cams on said shaft, a plurality of cam-follower interponents arranged each between a respective one of said cams and said tension-device, 55 and selectively controlled means for shifting said interponents to carry any desired one of them into operative relation with its respective cam and said tension device.

3. An intermittent thread-tension for sewing 60 machines including a spring closed tension-device, a rotary shaft, a primary tension-controlling cam on said shaft, an auxiliary tension-controlling cam on said shaft, and an interponent between said auxiliary cam and tension-device 65 shiftable from an operative to an inoperative position.

4. An intermittent thread-tension for sewing machines including a spring closed tension-device, a rotary shaft, a primary tension-controlling cam on said shaft, an auxiliary tension-controlling cam on said shaft, and an interponent between said cam and tension-device shiftable from an operative to an inoperative position, 70 said interponent being in the form of an end- 75

- wise movable bar having a thickened operative cam-follower portion.
5. An intermittent thread-tension for sewing machines including a spring-closed tension-device, a rotary shaft, a nest of tension-controlling cams on said shaft, a plurality of cam-follower interponents arranged each between a respective one of said cams and said tension-device, said interponents being each in the form of an 10 endwise shiftable bar having a thickened cam-follower portion, said thickened portions being at different positions endwise of said bars, and means for shifting said bars endwise to render a desired one of said interponents operative.
- 15 6. An intermittent tension-device for sewing machines comprising a tension-seat, a tension-head, an endwise movable rod passing through said seat and head, spaced shoulders on said rod between which said head has a limited movement lengthwise of and relative to said rod, a relatively strong spring for moving said rod in a direction to carry said head toward said seat, a relatively weak spring carried by said rod and applied to said head to yieldingly urge the lat- 20
- ter toward said seat, and a tension-controlling cam for moving said rod endwise in opposition to said strong spring.
7. An intermittent thread-tension device comprising, a frame including a tension-seat, an endwise movable rod passing through said seat and having fixed and adjustable shoulders thereon, a tension-head disposed on said rod and movable lengthwise of said rod between said shoulders, a spring carried by said rod and applied to said tension-head, and a second spring applied to said rod to move the latter in a direction to carry said tension-head toward said tension-seat. 5
8. An intermittent thread-tension for sewing machines including a tension-device, a rotary shaft, a nest of tension-operating cams fixed on said shaft, and means, movable at the will of the operator and shiftably interposed between said cams and said tension-device, to render any 10 selected one of said cams operative upon said tension device. 15
